DESIGN FOR A WEDDING SHEET

Frank B. Siegrist, Kansas City, Mo.

Application June 29, 1934, Serial No. 52,399

Term of patent 14 years

To all whom it may concern:

Be it known that I, Frank B. Siegrist, a citizen of the United States of America, residing at Kansas City, in the county of Jackson and State of Missouri, have invented a new, original, and ornamental Design for a Wedding Sheet, of which the following is a specification, reference being had to the accompanying drawing, forming part thereof, in which

Fig. 1 is a perspective view of a wedding sheet showing my new design.

Fig. 2 is an enlarged view of a portion of the wedding sheet showing my new design.

Fig. 3 is a sectional view taken along the line 3—3, Fig. 2.

The dominant feature of the design resides in the flower-like border surrounding the wedding invitation panel.

I claim:

The ornamental design for a wedding sheet as shown and described.

FRANK B. SIEGRIST.
